CASSETTE HOLDER

Roger E. Van Wyngarden, 5806 Rosslyn Ave.,
Indianapolis, Ind. 46220, and Mark E. Brackemyre,
1117 Dellwood Drive, Mooresville, Ind. 46158

Filed Mar. 30, 1972, Ser. No. 239,836

Term of patent 14 years

Int. Cl. D3—02

U.S. Cl. D87—1 D

FIG. 1 is a top plan view of a cassette holder showing our new design, the bottom being the same in appearance;

FIG. 2 is a side elevational view looking in the direction of the arrows 2—2 of FIG. 1 the opposite side being the same in appearance as the side shown;

FIG. 3 is an end view looking in the direction of the arrows 3—3 of FIG. 1;

FIG. 4 is an end view looking in the direction of the arrows 4—4 of FIG. 1; and

FIG. 5 is a view partially in section taken on the line 5—5 of FIG. 3.

We claim:

The ornamental design for a cassette holder, as shown and described.
